UNITED STATES PATENT OFFICE.

JOSEPH ROHLMANN, OF ST. JOSEPH, MISSOURI.

CARVING-MACHINE.

SPECIFICATION forming part of Letters Patent No. 444,306, dated January 6, 1891.

Application filed August 26, 1889. Serial No. 322,001. (No model.)

To all whom it may concern:

Be it known that I, JOSEPH ROHLMANN, of St. Joseph, in the county of Buchanan and State of Missouri, have invented a new and 5 Improved Carving-Machine, of which the following is a full, clear, and exact description.

The invention relates to wood-working machinery; and its object is to provide a new and improved carving-machine which is simple and durable in construction, very effective in operation, and adapted to carve simultaneously a number of blocks after one pattern.

The invention consists in certain parts and 15 details and combinations of the same, as will be described hereinafter, and then pointed out in the claims.

Reference is to be had to the accompanying drawings, forming a part of this specification, 20 in which similar letters of reference indicate corresponding parts in all the figures.

Figure 1 is a front view of the improvement, with parts in section. Fig. 2 is a sectional side elevation of the same on the line $\alpha\alpha$ of 25 Fig. 1. Fig. 3 is a plan view of the same. Fig. 4 is a sectional front view of part of the improvement on the line $y\gamma$ of Fig. 2. Fig. 5 is an enlarged front view of one of the cutters. Fig. 6 is a sectional side elevation of the 30 same on the line $z\zeta$ of Fig. 5. Fig. 7 is a sectional side elevation of the tool-chuck, and Fig. 8 is a plan view of the same.

The improved carving-machine is mounted on a suitably-constructed frame A, provided 35 on each side with suitable bearings for guiding vertical screw-rods B, rigidly connected at their upper ends with the side rails C and C', respectively, on which are mounted to slide transversely the runners D', secured on the 40 under side of the table D, adapted to support the pattern E and the blocks E' to be carved after the pattern E.

On each of the screw-rods B screws a nut B', formed on its outside like a sprocket-wheel, over which passes an endless sprocket-chain B², also passing over a sprocket-wheel B³, secured on the vertical shaft B⁴, mounted to turn in suitable bearings on the main frame A. A hand-wheel B⁵ is fastened on the top 45 of the said shaft B⁴, and serves to turn the latter, so as to turn the sprocket-wheel B³, whereby the sprocket-chain B² is set in motion and turns simultaneously the several nuts B', in order to raise or lower the screw-rods B, and consequently the side rails C C', 55 supporting the table D.

Over the pattern E is held a tracing-tool F, and on top of the several blocks E' operate the cutters G, held, with the tracing-tool F, on the frame H, which is counterbalanced and 60 universally jointed, so as to give any desired motion to the tracing-tool and the several cutters. The tracing-tool F is fastened into a socket F' by means of a set-screw F², and the said socket F' is provided with two bolts F³ 65 and F⁴, extending horizontally and passing through beams H' and H² of the frame H. The beams H' and H² extend longitudinally in front of the machine, are placed parallel with each other, and connected at their ends 70 by rods H³ and H⁴, each provided with two bolts H⁵ and H⁶, passing into the beams H' and H². These bolts H⁵ and H⁶ are in the nature of horizontal pivots connecting beams H' and H² to rods H³ H⁴, so as to permit the 75 beams to approach each other like parallel-motioned bars, the pivotal connection of bolts H⁵ H⁶ to beams H' and H² being substantially the same as the pivotal connections of bolts G¹⁰ to said beams, as shown in Figs. 5 and 6, 80 more fully described hereinafter.

On the rods H³ and H⁴, between the beams H' and H², are mounted to turn the sleeves I and I', each engaged by the pointed ends of set-screws J², screwing in a ring J or J', respectively, each supported on the pointed ends of the set-screws K², screwing in the forked ends of the brackets K and K', respectively. The pivots K², which connect the rings to the brackets, form one axis of oscillation, and the 90 pivots J², which connect the rings to the sleeves I I', form another axis of oscillation at right angles to K², which together constitute a universal joint. The pivots J², acting in harmony with bolts H⁵ H⁶, permit the beams 95 H' H² to move like parallel bars, as indicated by the dotted arcs of oscillation s s, Fig. 1. The brackets K K' are fulcrumed at their rear ends at K³ in the pulley-frame L, provided with suitable bearings, in which turns 100 the shaft L', engaged at its ends by the set-screws N', held in the lower end of a swing-

ing frame N, supported near its upper end on set-screws N², screwing in the standards A', erected on the rear of the main frame A. The upper ends of the standards A' are connected 5 with each other by a cross-frame A².

In the swinging frame N, in line with the set-screws N², is held in suitable bearings a main driving-shaft O, provided with fast and loose pulleys O' and O², respectively, connected in the usual manner with machinery for imparting a driving motion to the carving-machine. On the shaft O is also secured a pulley O³, over which passes a belt O', also passing over a pulley L², secured on the shaft 15 L' of the pulley-frame L. When the shaft O is rotated, the shaft L' is set in motion by the connection above described.

The front ends of the rearwardly-extending brackets K and K' are supported on a 20 bail P, extending upward and supported in its middle on a rod P', hung on a sleeve P², held adjustably on the weighted lever P³, fulcrumed on a shaft P⁴, mounted to turn in suitable bearings on an arm Q, pivoted at Q' 25 to a bracket Q², extending from the top of the cutting-frame A², previously mentioned. A weight P⁵ is held on the lever P³ and can be adjusted on the said lever to any desired position by a set-screw or other means. The 30 weight P⁵ serves to counterbalance the brackets K K' and the frame H and its contents supported on the front ends of the said brackets.

The swinging frame N is provided on each 35 side with upwardly-projecting arms N³, each supporting near its upper end a weight N⁴, which serves to move the frame N at all times back into a vertical position. It will be seen that the frame H, with the cutters G and the 40 tracing-tool F, is free to swing forward and backward, turning on the set-screws K². Said frame is also free to swing sidewise, turning with its rods H³ and H⁴ in the sleeves I and I', respectively, supported by the set-screws 45 J² from the rings J and J'. The sidewise motion of the frame H is permitted by the brackets K and K', as the latter have their vertical pivots at their rear ends in the frame L.

50. The frame H, when in a vertical position, can be moved forward and backward without turning, as the frame N permits such movement, turning on the set-screws N'. The frame H can also be raised and lowered by 55 the frame L turning on the set-screws N' in the swinging frame N. The weight P⁵ counterbalances the frame H and its contents when raised or lowered to any position. The counterbalancing-lever P³ follows the movement of the frame H and the brackets K K' on account of being pivoted on the shaft P⁴, turning on the pivoted arm Q. Thus it will be seen that the tracing-tool F and the cutters G can be moved in any desired position. 60 Each of the cutters G is provided with a cutting-tool G', the shank of which fits into a

split sleeve or chuck G², passed into a central aperture formed in the lower screw-threaded end G³ of the spindle G⁴, mounted to turn in the spindle-frame G⁵, carrying a pulley G⁶, 70 over which passes a belt L⁴, also passing over a corresponding pulley L², fastened on the shaft L' of the pulley-frame L.

On the threaded end G³ of the spindle G⁴ screws a nut G⁷, provided on its lower end 75 with inclined flanges G⁸, adapted to press against a conical offset G⁹, formed on the lower end of the split sleeve G², so as to press said sleeve together at its lower end to fasten the tool G'. (See Figs. 6, 7, and 8.) From 80 the spindle-frame G⁵ extend horizontally the bolts G¹⁰, passing through the beams H² and H² of the frame H in the same manner as the bolts F³ and F⁴ pass through the said beams, as before described in reference to the tracing-tool.

The spindle-frame G⁵ is provided with the usual oil-cups R for oiling the spindle G⁴. A handle G¹¹ is held on the spindle-frame G⁵, and serves for conveniently moving the latter whenever desired. On the lower end of the handle G¹¹ is held a drip-cup G¹² for gathering the drip-oil of the spindle G⁴ and to prevent the oil from passing onto the carved work. 95

The operation is as follows: When the shaft O is rotated, the spindles G⁴ of the cutters G are turned, the tools G' turning with the spindles. The operator takes hold of the frame H and manipulates the said frame, so that the tracing-tool F moves over the ornament already formed on the pattern E, pressing the frame H downward, so that the several tools G' cut with their cutting bottom edges into the wooden blocks E'. The surplus material 105 on the blocks E' is removed by the tools G', and as the said tools operate in correspondence with the movement of the tracing-tool F the ornament finally appearing in the blocks E' corresponds to the ornament on the pattern E. 110

It will be seen that as the operator is enabled by the peculiar construction of the machine to press the tracing-tool in any desired position, so that the cutting-tools assume a 115 like position, all parts of the ornament can be readily traced and reproduced in the blocks E' by the action of the cutting-tools G'. It will further be seen that by the simple movement of the hand-wheel B⁵ the table D, carrying the pattern E and the blocks E', can be readily raised or lowered, according to the thickness of the blocks to be operated on. It will further be seen that the table D can be easily moved forward and backward on the 120 rails C and C', so as to bring the blocks directly under the tracing-tool F and the tools G'. It will further be seen that the frame H, carrying the tracing-tool and the cutters, can be very easily manipulated on account of 125 being counterbalanced in any and every position by the weight P⁵. 130

Having thus described my invention, what I claim as new, and desire to secure by Letters Patent, is—

1. In a carving-machine, the combination, with a frame carrying the cutters and tracing-tool, of universal joints supporting the ends of the said frame, pivoted brackets supporting the said universal joints, and a counterbalanced lever connected with the free ends 10 of the said brackets, substantially as shown and described.
2. In a carving-machine, the combination, with a frame carrying the cutters and tracing-tool, of universal joints supporting the ends 15 of the said frame, pivoted brackets supporting the said universal joints, a counterbalanced lever connected with the free ends of the said brackets, and a pivoted arm carrying a shaft on which the said lever is pivoted, substantially as shown and described.
3. In a carving-machine, the combination, with a main frame, of screw-rods guided in the said frame, side rails supported on the said screw-rods, a table held to slide horizontally on the said side rails, nuts screwing on the said screw-rods, and an endless chain passing 25 over the said nuts and adapted to turn all the nuts simultaneously, substantially as shown and described.

4. In a carving-machine, the combination, 30 with a main frame, of screw-rods guided in the said frame, side rails supported on the said screw-rods, a table held to slide horizontally on the said side rails, nuts screwing on the said screw-rods, an endless chain passing 35 over the said nuts and adapted to turn all the nuts simultaneously, and means, substantially as described, for imparting a traveling motion to the said chain to turn the said nuts, as set forth. 40

5. In a carving-machine, the combination, with a main frame, of screw-rods guided in the said frame, side rails supported on the said screw-rods, a table held to slide horizontally on the said side rails, nuts screwing on the said screw-rods, an endless chain passing 45 over the said nuts and adapted to turn all the nuts simultaneously, a sprocket-wheel mounted to turn in the said frame and over which passes the said chain, and means, substantially as described, for turning the said sprocket-wheel, substantially as shown and described. 50
